US00D928132S

(12) **United States Design Patent** (10) **Patent No.:** **US D928,132 S**
(45) **Date of Patent:** **** Aug. 17, 2021**

(54) **PORTABLE ELECTRONIC DEVICE**

(71) Applicant: **HTC Corporation**, Taoyuan (TW)

(72) Inventors: **Lee-Wei Chen**, Taoyuan (TW);
Yien-Chun Kuo, Taoyuan (TW);
Hung-Yu Chen, Taoyuan (TW);
Meng-Sheng Chiang, Taoyuan (TW)

(73) Assignee: **HTC CORPORATION**, Taoyuan (TW)

(**) Term: **15 Years**

(21) Appl. No.: **29/680,755**

(22) Filed: **Feb. 19, 2019**

Related U.S. Application Data

(62) Division of application No. 29/597,162, filed on Mar. 15, 2017.

(51) **LOC (13) Cl.** **14-03**

(52) **U.S. Cl.**

(57) **CLAIM**

The ornamental design for a portable electronic device, as shown and described.

DESCRIPTION

FIG. 1 is a perspective view of a portable electronic device in accordance with our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line portions of the portable electronic device represent unclaimed portions of the claimed design and form no part thereof.

1 Claim, 6 Drawing Sheets
